UNITED STATES PATENT OFFICE

WALLACE E. C. STONE, OF LOS ANGELES, CALIFORNIA

DESIGN FOR AN AEROPLANE-WING COURSE LIGHT

Application filed April 17, 1930. Serial No. 35,275. Term of patent 14 years.

To all whom it may concern:

Be it known that I, WALLACE E. C. STONE, a citizen of the United States, residing at Los Angeles, in the county of Los Angeles and State of California, have invented a new, original, and ornamental Design for Aeroplane-Wing Course Light, of which the following is a specification, reference being had to the accompanying drawing, forming part thereof.

Fig. 1 is a top plan view of an aeroplane wing course light, showing my new design.

Fig. 2 is a side elevation thereof.

Fig. 3 is a front elevation thereof.

I claim:

The ornamental design for an aeroplane wing course light, as shown.

W. E. C. STONE.
